PAIR OF SPECTACLES

Jack Bloch, Leominster, Mass., assignor to Foster Grant Co., Inc., Leominster, Mass., a corporation of Delaware

Filed July 7, 1969, Ser. No. 18,098

Term of patent 14 years

Int. Cl. D16—08

U.S. Cl. D57—1

FIG. 1 is a perspective view of a pair of spectacles showing my new design;

FIG. 2 is a front elevational view thereof.

FIG. 3 is a fragmentary rear inverted view of the pair of spectacles having a sectional portion taken on line 3—3 of FIG. 2.

The spectacles are fragmentarily shown in FIG. 3 for convenience of illustration.

The side not shown has substantially the same appearance as the side shown.

I claim:

The ornamental design for a pair of spectacles, substantially as shown and described.
